TELEPHONE LOCK

David Engelson, New York, N. Y.; Isaac Davidson
executor of David Engelson, deceased

Application September 17, 1938, Serial No. 230,376

3 Claims. (Cl. 179—189)

The present invention is directed to locking devices for rotary dials associated with the base of a telephone instrument and is especially concerned with locking and closure means to preclude unauthorized use of the telephone for outgoing calls without however interfering with normal operation of the telephone for reception of incoming calls. The invention has as one object the provision of a split closure comprising 5 pivotally connected and overlapping sections for covering the dial of the telephone and including means cooperating with the fixed finger stop associated with the rotary dial to prevent rotation of the closure. The invention has as a further 10 object the provision of a split closure of the character referred to wherein the complementary sections each include a curved lip cooperating to interlock the rim of the rotary dial to preclude removal of the closure while in its closed position 15 on the dial. The invention has a further object to provide a relatively light weight but durable and improved closure having pivotally connected sections or components to permit lateral separation thereof in respect to the dial and to allow 20 convenient closing of the sections over the dial and including means adapted to register in the closed relation of the sections to receive detachable locking means to prevent pivotal separation 25 of the sections. Other objects, advantages, and features of the invention will be more apparent 30 from a consideration of the following detailed description considered in connection with the accompanying drawing in which:

Fig. 1 is a perspective view of my closure locking device shown partly broken away.

Fig. 2 is a plan view of Fig. 1.

Fig. 3 is a sectional view taken along the line 3—3 of Fig. 2.

Fig. 4 is a sectional view on the line 4—4 of Fig. 2.

Fig. 5 is a fragmentary elevational view of the lower section looking in the direction of the arrows on the line 5—5 of Fig. 1.

Fig. 6 is a bottom view of Fig. 5 and showing a portion of the fixed finger piece locked in a recess of the lower closure section.

Fig. 7 is a fragmentary view of the split closure, particularly illustrating the stop means to permit the front eyes of the complementary sections of the closure to automatically register.

According to the invention a locking closure generally denoted 10 is positioned over a rotary dial 11 of a telephone instrument 12. This closure comprises substantially semi-circular upper and lower components or sections 13 and 14 hav-

ing their adjacent marginal portions 15 and 16 disposed in overlapping relation in the closed position of the sections as illustrated in full lines shown in Figs. 2 and 3.

The upper and lower sections each include at 5 its rear portion an eye 17 through which a fulcrum pin 18 passes. By this arrangement the upper and lower sections are hingedly associated and it follows the complementary closure sections 13 and 14 can be readily spread apart as indicated 10 by the dash and dot lines in Fig. 2 and if spread apart they may be readily brought towards one another to assume their closed positions as illustrated by the full lines in Fig. 2.

Each of the closure sections 13 and 14 is provided with a circumferentially arranged depending curved lip 19 defining a groove for receiving the rotary rim of the finger actuated dial 11. If therefore the complementary sections are over the dial and closed, the depending lips 19 embrace 15 the rim of the dial and lock the closure 20 against upward displacement.

The upper and lower sections 13 and 14 are provided with a central boss 20 and 21 respectively and these in part embody the adjacent overlapped portions or inner margins 15 and 16 of the sections 13 and 14. The bosses 20 and 21 in the closed position of the sections in fact constitute a central raised hollow housing for receiving and enclosing the conventional indicia 25 carrying member 22 secured to the rotary dial.

Extending outwardly from boss 21 of the lower section 14 but struck out from the latter is the arcuate boss 23 constituting a socket for closely but disengageably housing the arcuate and fixed 35 finger piece stop 24 mounted on the base of the telephone. Arcuate boss 23 has its sides 25 closely but removably straddling sides 26 of the fixed stop 24 to prevent rotation of the closure relative to the dial and to supplement such action, vertical end portion 27 of the fixed stop 24 fits closely 40 but removably into locking recess 28 of the channel or socket 28 formed in part in the arcuate lip 19 of the lower pivoted cover section 14.

With the closure mounted on the dial and closed 45 as shown in Fig. 2 or 3, the front perforated ears 29 of the cover sections 13 and 14 are disposed in registration, that is to say, if these complementary cover sections are fully closed the perforations of ears 29 automatically line up. This 50 is accomplished when the lower ear 29 of the lower section 14 strikes biased terminal 30 of the depending curved lip 19 of the upper cover section 13. Thereafter the hasp 31 of a key controlled padlock 32 is inserted through the 55

- hasp sustaining ears 29 and locked as is well understood. It follows that the complementary cover sections are locked against pivotal separation and against removal from the dial. In such 5 relation the closure 10 is also prevented from rotation relative to the rotary dial. Thus incoming telephone calls may be received although the dial cannot be manipulated for unauthorized outgoing calls.
- 10 To detach the closure from the dial, padlock 32 is first unlocked, hasp 31 is removed from the perforations of the superimposed ears 29, the upper section is swung or hinged laterally relative to the dial, and the lower section is lifted 15 from the dial. Thus the closure is removed and access can now be had to the dial to permit authorized use thereof for outgoing calls.

In the broader aspects of the invention, I do not desire to be understood as limiting the embodiment thereof to details herein shown illustratively as a wide variety of modifications may be made within the scope of the invention.

I claim:

1. In a locking device for a rotary telephone 25 dial associated with a fixed stop and having a raised indicia carrying member, the combination of, a closure for the upper surface of said dial comprising complementary cover sections having centrally arranged raised and overlapping por- 30 tions for closing said member and each having a depending curved lip for removably interlocking with the rim of said dial, one of said sections having means cooperating with said stop to prevent rotation of said closure relative to said stop, means hingedly connecting corresponding por- 35 tions of said sections to permit pivotal separation or closing of said sections, and disconnectable locking means cooperating with said sections to prevent pivotal separation thereof.

- 40 2. In a locking device for a rotary telephone

dial associated with a fixed stop and having an indicia carrying member, the combination of, a closure for the upper surface of said dial comprising complementary cover sections having centrally arranged and overlapping and substantially 5 diametrically disposed inner portions for encompassing said member and each having a depending curved lip for removably interlocking with the rim of said dial, one of said sections having a hollow boss including sides straddling said stop 10 to prevent rotation of said closure relative to said stop, means hingedly connecting corresponding portions of said sections to permit pivotal separation or closing of said sections, lock sustaining means carried by said sections, and disconnectable locking means removably associated with said sustaining means and cooperating with said sections to prevent pivotal separation thereof.

3. In a locking device for a rotary telephone dial associated with a fixed stop and including a central raised part, the combination of, a substantially disc shaped closure for the upper surface of said dial comprising complementary substantially semi-circular sections each having a depending circular lip for interlocking with the rim of said dial and including centrally arranged and overlapping and separable bosses for housing said raised part, a hinged connection at a pair of corresponding end portions of said sections to permit pivotal separation or closing thereof, one 30 of said sections having a hollow struck out housing for receiving said stop, one of said lips having a recess including walls forming a part of said housing and closely straddling the lower part of the sides of said stop, said sections having 35 eyes, means to automatically align said eyes upon pivotal closing of said cover sections, and disconnectable locking means sustained by said eyes to prevent pivotal separation of said sections.

DAVID ENGELSON. 40
